Attorney

UNITED STATES PATENT OFFICE

JOSEPH PROVIDENTI, OF CHARLESTON, WEST VIRGINIA

BANJO

Application filed February 17, 1931. Serial No. 516,420.

This invention relates to an improved banjo involving a refined body construction applicable to either the conventional five string banjo, or to the tenor and plectrum types of banjo.

It is a matter of common knowledge to those skilled in the art to which the invention relates that ordinary banjos have an adjustable drum-like or skin head which is susceptible to varying defects according to weather and atmospheric conditions. Then too, as a general rule, the ordinary banjo is equipped with a resonator. The usual resonator is provided with a multiplicity of annular tone holes. The body of the conventional banjo, that is, the rim is as a general rule, imperforate.

The present inventive conception involves an idea requiring a change in the construction of details designed to permit the development of a more resonant and voluminous quality of tone of a loud and full resounding sonorous character, this being accomplished by constructing the banjo with the following 25 distinguishable characteristic details.

First, my improved banjo includes a one-piece disc-like wooded head rigidly secured to the shell or rim of the body and preferably constructed of spruce wood of a selected and 30 well-seasoned variety, whereby to provide a sensitive and vibrant rest for the bridge.

Secondly, the improved banjo body is individualized when compared with prior art devices in that it includes an all-wood, preferably spruce wood resonator, permanently attached to the rim of the instrument of a greater diameter than said rim, said resonator being imperforate for the purpose of prolongation and reinforcement of sound by 40 sympathetic vibration.

Third, the annular shell or rim of the body is of wood and provided with circumferentially spaced relatively large tone holes designed 45 to allow free emanation of sound waves.

The purpose of a composite wooden structure of the above type is to provide a systematic organization or ensemble of parts which co-operate in a coherent and harmonious 50 manner to provide the quality of tone which

is most loud and resonant and characterized by appealing carrying properties.

In the drawings:

Figure 1 is a top plan view of a banjo constructed in accordance with the present invention.

Figure 2 is a side elevation or edge view of the same.

Figure 3 is a horizontal section on the line 3—3 of Figure 2.

Figure 4 is a cross section on the line 4—4 of Figure 3.

In Figure 1, and the following Figure 2 it will be observed that the resonator is denoted generally by the reference character 5, the head is indicated at 6 and the annular shell or rim at 7. The neck 8 is conventional in length and proportion and provided with customary frets 9 and with tuning pegs or keys 10. The strings are indicated at 11, fastened to the customary tail piece 12 and passed over a conventional bridge 13 seated on the head as is usual.

The improved head 6 is formed from a single ply of spruce wood and is rigidly secured to the top edge of the rim 7. Around the peripheral edge of the head is a protecting and ornamental band 14. The resonator comprises spruce wood including a disc-like part 15 having an ornamental and marginal protecting band 16.

As is customary, the resonator is of a diameter greater than both the head and shell of the body. The shell is also of wood and includes suitably lined circumferentially spaced tone holes 17 for escape of the sound waves. The resonator also includes a ring-like part of L-shaped cross section whose vertical flange is indicated at 18 and whose horizontal flange is indicated at 19. Both of these flanges as well as the disc 15 are imperforate.

On the interior of the disc 15 are reinforcing strips 20. It is evident from the description and drawings that the improvement and construction resides only in the body of the instrument. It may be added however that the head or top 6 is preferably provided with a suitable shaped tone outlet opening as indicated at 21 in Figure 1.

I shall not attempt to expound the theory

on which the improved tonal results are founded for it is difficult to know just why it is that this particular all-wood hollow body with the tone holes in the rim provides for what I believe to be, a more pleasing and desirable quality of tone as compared to the usual harsh sounding banjos particularly of the tenor variety.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

20 An all-wood banjo body comprising an annular rim provided with circumferentially spaced tone holes, a relatively thin disc-like head of spruce wood forming a top for the rim and rigidly secured to the adjacent edge 23 of said rim, a two-part resonator comprising a disc-like part of a diameter greater than the head and rim, said disc-like part being of one solid piece of spruce wood, the remaining part of the resonator including an im- 30 perforate ring-like member of general L-shaped cross section having one flange secured rigidly to the marginal edge portion of the disc-like part and having its remaining flange secured to the exterior face of the low- 33 er remaining edge portion of said rim, said last named flange being disposed in a plane spaced from the aforesaid tone holes.

In testimony whereof I affix my signature.

JOSEPH PROVIDENTI.
